DESK SET OR THE LIKE

Alwin J. Stahel, New Brighton, Minn., assignor to Arthur Salm Inc., Chicago, Ill.

Filed Jan. 2, 1973, Ser. No. 319,992

Term of patent 14 years

Int. Cl. D19—02

U.S. Cl. D74—5 B

FIG. 9

FIG. 1 is a perspective view of a desk set showing my new design;

FIG. 2 is an exploded perspective view thereof;

FIG. 3 is an enlarged scale top plan view;

FIG. 4 is a right end elevational view thereof;

FIG. 5 is a left end elevational view thereof;

FIG. 6 is a bottom plan view thereof;

FIG. 7 is a front elevational view thereof;

FIG. 8 is a right end elevational view of the holder portion; and

FIG. 9 is a perspective view of the desk set showing the letter opener in an inverted position.

I claim:

The ornamental design for a desk set or the like, substantially as shown and described.
